UNITED STATES PATENT OFFICE.

EZEKIEL VAN NOORDEN, OF BROOKLINE, MASSACHUSETTS.

VENTILATOR.

Application filed March 10, 1926. Serial No. 93,678.

The invention relates to that type of ventilator having a rotary head or cowl and especially to that type in which the opening or passage into and through the head is controlled by a damper having attached to it a flexible connection for operating the damper.

The special object of the invention is to provide a very simple but particularly efficient arrangement for so mounting the head on the body of the ventilator and for so fixing the head to the body as will ensure freedom of rotation especially when the head is being subjected to lateral strains.

The invention can best be seen and understood by reference to the drawings in which—

Figure 1 shows the ventilator mainly in cross vertical section, certain of the interior parts being shown in side elevation.

Fig. 2 is a section on the line 2—2 of Fig. 1.

Fig. 3 is a vertical section showing in enlarged detail a portion of the structure shown in Fig. 1.

1 represents the body of the ventilator. This is generally circular in form and is mounted on any suitable base 2.

3 is the rotary head or cowl generally circular in form and which is fitted with the usual vane or wing 4 by which it is rotated. On one side the head has an outlet controlled by a hinged damper 5 operated by a chain or flexible connection 6 secured to the damper. The chain extends back to pass over a pulley 7 arranged in the top of the head and from which pulley the chain depends.

The head is mounted to rotate on the body of the ventilator as follows:

The body 1 of the ventilator on the inside at the top is provided with an annular rail 8. This rail occupies a position spaced from the exterior wall of the body and preferably not far downwardly and inwardly removed from the top edge 9 of the body.

45 The rail is concentric with the vertical centre of the body. It is fixed to the body by suitable fastenings or bolts 10 which pass through suitable space blocks 11 interposed between the rail and the body. Thus dis-

50 posed and secured, the rail becomes a body fixture. In similar manner the head 3 of the ventilator on the inside at the bottom is provided with an annular rail 12 which occupies a position spaced from the exterior wall of the head and preferably not far upwardly and inwardly removed from the bot-

tom edge 13 of the head. The rail 12 is concentric with the vertical centre of the head and is fastened to the head by suitable bolts or fastenings 14, space blocks 15 being interposed between the rail and head through which the fastenings extend. Thus disposed and arranged, the rail 12 becomes a fixture with the head and turns with it.

The mounting of the head, upon the body 65 of the ventilator, is such that the vertical centres of the head and body will be in alignment and when thus arranged the two rails 8 and 12 will occupy positions in vertical alignment one above the other in spaced relation to one another. Interposed between the two rails, thus arranged, are a number of wheels 16, not less than three in number, four preferably being employed. It is on these wheels that the head is mounted to rotate, the wheels running on the respective rails as the head turns. The wheels are held in proper spaced relation to one another and otherwise retained to maintain their positions on the respective tracks in a manner 70 presently to be explained, reference being first made, however, to the manner in which the head is fixed to the body against lateral displacement and in a manner to permit of the rotation of the head on the wheels as 75 aforesaid.

Extending diametrically crosswise through the body, preferably at a point just below its track 8 is a crossbar 18. This bar is provided with flanges at its opposite ends by 80 which it is fixed to the opposite sides of the body by suitable bolts or fastenings 19. This bar has secured to it a strap 20. This strap together with the bar 18 is bent at their respective centres to form an eye 21 85 concentric with the vertical centre of the body.

The head is similarly fitted with a crossbar 22 which extends diametrically across the head at a point preferably just above its track 12. The bar 22 is provided with flanged ends by which it is fixed to the opposite sides of the head by suitable fastenings or bolts 23. The bar has secured to it a strap 24 which together with the bar is 100 bent to form an eye 25 concentric with the vertical centre of the head. Passed through the eyes 21 and 25, thus fixed respectively to the body and head, is a vertical pin 26 with extension at its opposite ends beyond 105 the respective eyes. Secured to the ends of the pin thus extending are collars 27, 28

which bear against the respective eyes. Thus the head and body are connected and upward displacement of the head prevented. The vertical pin 26 also functions to prevent any undue lateral displacement of the head with relation to the body. The bars 18 and 22 and straps secured to them, which form the respective eyes through which the pin extends, are preferably of flat bar metal and provide relatively long bearings for the pin at the points of the respective eyes. With the pins fitting snugly within the eyes the head has little chance for lateral displacement. In this same connection, if desired, the eye 21 may be bound fixedly to the pin preventing its rotation, but allowing free rotation of the head.

With the head thus mounted to turn upon the respective wheels and with the pin 26 thus connecting the head to the body, a relatively long bearing surface is left along the pin between the eyes 21 and 25. Arranged to turn upon the bearing thus provided by the pin is a hub 30 from which extend 25 spokes 31 like the spokes of a wheel. These spokes extend through the wheels 16, maintaining the wheels in proper spaced relation to one another and providing axles on which the wheels may turn as they run around on the respective rails during the turning of the head. To hold the wheels in proper radial spaced relation to the hub around which they are turning, or in other words to prevent lateral displacement of the wheels from 35 the respective rails, the spokes 30 are provided with pins 32 passed through them at points just adjacent the opposite sides of the wheels, thereby boxing the wheels and making them to track right on the respective rails during the rotation of the head.

With a head thus mounted to rotate a space 33 will be left between the top edge 9 of the body and the bottom edge 13 of the head. This space should be as small as possible, but leave sufficient clearance between the body and head to prevent contact between the body and head during the rotation of the head. The space is enclosed by means of a guard in the nature of an apron 34 fixed to the head.

It is also to be observed that the vertical pin 26, which operates to hold the head onto

the body, is a hollow pin and through it the chain 6, which operates the damper, extends, the pin thus acting as a guide for the chain 55 as well as preventing the chain from interfering with any of the operating parts during the rotation of the head.

Having thus fully described my invention, I claim and desire to secure by Letters 60 Patent of the United States:—

1. In a ventilator, the combination comprising the fixed body of the ventilator, a rotary head, circular spaced rails fastened respectively to the body and head of the 65 ventilator, wheels interposed between the rails to track thereon and on which wheels the head turns, a vertical pin centrally arranged within the ventilator, fixtures connected to the body and head respectively 70 supporting said pin by which it will function to fasten the head to the body with permitted rotation of the head, a hub-forming member common to all of said wheels rotatable inside the ventilator on said pin providing a bearing therefor, and connections between said member and wheels by which the member will function to retain the wheels on said rails in proper spaced relation to 75 one another.

2. In a ventilator, the combination comprising the fixed body of the ventilator, a rotary head having a discharge outlet and a damper controlling said outlet, circular spaced rails fastened respectively to the 80 body and head of the ventilator, wheels interposed between the rails to track thereon and on which wheels the head turns, a hollow vertical pin or tube centrally arranged within the ventilator, fixtures connected to the body and head respectively supporting the pin by which it will function to fasten the head to the body with permitted rotation of the head, a hub-forming member common to all of said wheels rotatable inside the ventilator on said pin providing a bearing therefor, connections between said member and wheels by which the member will function to retain the wheels on said 85 rails in proper spaced relation to one another, and a flexible connection for operating said damper extending through said pin.

EZEKIEL VAN NOORDEN.
